UNITED STATES PATENT OFFICE

JAMES E. ECKERSLEY, OF ABERDEEN, WASHINGTON, ASSIGNOR OF ONE-HALF TO
ALEXANDER POLSON, OF HOQUIAM, WASHINGTON

SET WORKS FOR WOOD CUTTING MACHINES

Application filed August 19, 1927. Serial No. 214,185.

The object of my invention is to provide a set works for wood cutting machines for such as a shingle, veneer, or shook machine, which by its connection to the "block" feeding rolls of such a machine, the block is fed toward the knife so that according to the setting the block will have been fed forward more at one end than the other, and with this and other objects in view, my invention 5 consists of the parts, and combination of parts as will be hereinafter fully set forth.

In the drawings:

Figure 1 is a top plan view of set works embodying my invention.

15 Figure 2 is a front elevation of Figure 1.

Figure 3 is a side elevation of one of the clutch cases, part being removed.

20 Figure 4 is a side elevation of Figure 3, parts being removed and parts being in section.

Figure 5 is a side elevation of the clutch case with one of the side walls removed.

25 Figure 6 is a vertical sectional view through a clutch case showing another embodiment.

The reference numerals 6 and 7 designate standards in which are mounted bearing sleeves 8 and 9, said sleeves being held in position by means of the caps 10. These sleeves 30 are revolvably mounted on the pedestals 6 and 7 and the ends of the drive shaft 11 are journaled within said sleeves. The sleeve 9 is provided at its inner end with the clutch member 12, and the sleeve 8 is provided at its 35 inner end with a similar clutch member 13.

A clutch member 14 is keyed to the shaft 11 by means of the pins 15 and extending from this clutch member 14 is a crank lever 16 which, in turn, is connected to a pitman 17 40 extending to a suitable source of power. The shaft 11 is provided with a swivel connection 18 at one end connecting the shaft lever 19 thereto whereby the shaft may be moved by said lever 19 into three positions so that 45 the shaft may be held in neutral position, or where the clutch member 14 is not connected to either the clutch member 12 or 13 of the sleeves 8 and 9; or the clutch member 14 may be thrown in operative connection with either 50 of the clutch members 12 or 13.

Mounted on the sleeve bearing 9 is a lever 20 and connected to the upper end of the lever 20 is a bell crank lever 21, the arm 22 of which is in the form of a quadrant and provided with an elongated arcuate slot 23 55 whereby the lever 21 may be adjusted to the desired position by means of the bolt and nut 24. A rod 25 is connected by means of the pin 26 to the bell crank lever 21, the other end of the rod being connected to a clutch case 27, to be hereinafter referred to, by means of the bolt and nut 28.

Mounted on the sleeve 8 is a lever 29 which is pivotally connected by means of the bolt and nut 30 to one end of the bell crank 31, 60 the arm 32 of which is in the form of a quadrant and is provided with an elongated arcuate slot 33 whereby by means of the bolt and nut 34 the position of the lever 31 may be fixed. To the crank lever 31 I pivotally secure one end of the rod 35 as at 36, the other end of the rod 35 being pivotally secured to the clutch member 37. The clutch case 37 is revolvably mounted on the feed or transmission shaft 39, and on this shaft 39 and on feed or transmission shaft 40 there are also revolvably mounted clutch cases 41 and 42 and 27 65 which will be hereinafter referred to, the clutch cases 27 and 41 being on the shaft 40 and maintained in spaced relation by means of the sleeve 43 likewise mounted on the shaft 40 while the clutch cases 37 and 42 are both mounted on shaft 39 and maintained in spaced relation by means of the sleeve 43a mounted 70 also on the shaft 39.

80 Clutch devices 27 and 41 are one-way clutches constructed to respectively rotate the shaft 40 in opposite directions, and clutch devices 37 and 42 are one-way clutches likewise constructed to respectively rotate the shaft 39 in opposite directions, clutch devices 27 and 37 acting to rotate the shafts 40 and 39 in a counterclockwise direction, while clutch devices 41 and 42 act to rotate the shafts 40 and 39 in a clockwise direction. 85 Clutch devices 27 and 42 are coupled to sleeve 9 so that when said sleeve 9 is connected to clutch member 14 and shaft 11 oscillated shaft 40 will be turned counterclockwise by clutch device 27 and shaft 39 will be simultaneously 90 95 100

turned clockwise by clutch device 42. On the contrary when sleeve 8 is connected to clutch member 14 and shaft 11 oscillated clutch device 37 will turn shaft 39 in a counterclockwise direction, while clutch device 41 will turn shaft 40 in a clockwise direction. The slotted quadrants 22 and 32 permit the throw of rods 25 and 35 to be varied on a working motion of shaft 11, while the quadrants 44 and 50 permit the throw of rods 46 and 52 to be correspondingly varied. It will thus be evident that the feed roll actuating shafts 57 may be operated to actuate the feed rolls for desired adjustments of the ends of the block being operated upon.

The clutch case 27 is provided with a quadrant 44 having an elongated arcuate slot 45 in which one end of the rod 46 is secured in any predetermined position by means of the bolt or nut 47 to regulate the throw of the rod 46, said rod being provided with a turn buckle 48 to take up slack in the rod. The other end of the rod 46 is connected by means of the bolt and nut 49 to the clutch case 42. Clutch case 37 in turn is provided with a quadrant 50 having an elongated arcuate slot 51 in which one end of the rod 52 is fixed in a predetermined position by means of the bolt and nut 53'. This rod 52 is also provided with a turn buckle 53 and is connected at its other end by means of the bolt and nut 54 to the clutch case 41, as clearly shown in Figure 2.

The subshaft 39 is connected at its inner end through a series of universal joints 55 by the spline and sleeve shaft 56 to the feed rollers 57 of the machine, and subshaft 40 is connected at its inner end through a series of universal joints 55a by the spline and sleeve shaft 56a to the feed roller 57a, which feed rollers may be like the feed rollers shown in my Patent No. 1,552,985 of Sept. 8, 1925.

Power being delivered through the pitman 17 and angle crank 16 to the shaft 11, then through the bell crank lever 29, rod 35 to the clutch case 37, thence through the quadrant 50 of the clutch case to the bar 52 to the clutch case 41.

As the clutch case 37 is operated clockwise for a given distance, clutch case 41 is operating anticlockwise, but not as far as the clutch case 37 on account of its quadrant connection to the clutch case 37, the line of arc being different.

Power being delivered to the power shaft 11, thence through bell crank lever 21, thence through the rod 25 to clutch case 27, and said clutch case through its quadrant transmits power to the rod 46 to the clutch case 41.

As the clutch case 27 is being operated for a given distance anticlockwise clutch case 42 is operated clockwise, but not as far as the clutch case 27 on account of its quadrant connection to the clutch case 27, the line of arc being different.

When power shaft 11 is operated for a given distance clockwise, clutch case 37 will travel clockwise and clutch case 41 will operate anticlockwise, both clutches turning the shafts on which they are mounted for a given distance, and when the clutch case 41 is operating in anticlockwise direction; and when clutch case 27 will be operating clockwise, clutch case 42 will be operating anticlockwise.

Subshafts 39 and 40 deliver power to the feed rolls 57, 57a of the machine through the universal joints and sleeve and spline shafts 55, 56, respectively. If the block of wood in the machine to be operated upon happens to be of more thickness at one end than at the other, and all thick butts should be cut from the thick end, then the set works may be manipulated by shifting power shaft 11 into either the sleeve 9 or the sleeve 8 as the case may be. If, as in Figure 1, the clutch member 14 is in engagement with the clutch sleeve 9 the action of the clutch cases would be as follows: clutch cases 27 and 42 would be operating on the feed rolls and the clutch cases 37 and 41 would stand stationary. If the power shaft were to be moved in the opposite direction the clutch member 14 would be in contact with the clutch sleeve 8 and would operate clutch cases 37 and 41 and they, in turn, would operate the shafts 39 and 40, the clutch cases 42 and 27 not operating.

The clutch cases have their own bearings on the shafts 39 and 40, being loosely mounted thereon, but on the inside of each there is a master gear fixed to the shaft.

Referring now to Figures 3 and 4 which is typical of all of the clutch cases, the master gear 58 is secured to the subshaft 40 by means of the key 59. A clutch cam 60 is mounted on a suitable shaft 61 having a roller bearing 62 at each end thereof, the roller bearing being mounted in recesses formed in the side walls of the casing. Said clutch cam has associated with it brake rolls 62' which are held in operative position by means of the springs 63. These brake rolls are adapted to go into clutching engagement with the surfaces 64 of the brake ring 65 which is pressed into the gear case.

A pinion gear 66 is keyed to the shaft 61 and meshes with the master gear 58. As shown, the clutch case is loosely mounted on the shaft 40, each side wall of the case forming a bearing on the shaft on either side of the master gear 58.

In Figure 6 I have shown a worm gear 67 as being substituted for the pinion 66, otherwise the construction is the same as has been described in connection with Figures 3, 4 and 5.

It will be understood that my machine may be used for cutting shingles, veneer and shooks.

Of course, it is understood that changes may be made in the relative arrangement of parts, and in the details of construction without departing from the spirit of my invention and the scope of the appended claims.

What I claim is:

1. In a machine of the character described, a power shaft, a clutch member keyed to said shaft, clutch members revolvably mounted on said shaft and adapted to engage with the said keyed clutch member, bell crank levers connected with said revolvably clutch members, a subshaft on each side of the power shaft, a series of one way clutches mounted on each of said subshafts, and rods connecting the said clutches of the subshafts with the said bell crank levers.

2. In a wood cutting machine of the character described, the combination with feed shafts for operating feed rolls for advancing the wood to a cutter, of a power shaft, a clutch member keyed to said power shaft, clutches revolvably mounted on said power shaft, means to shift the power shaft relatively to the revolvably mounted clutches, a pair of one-way reversely acting clutches on each of said feed shafts, means connecting each of the said revolvably mounted clutches respectively to one of the clutches of one of the feed shafts and means connecting another of the clutches of one feed shaft with a clutch on the other of said feed shafts.

3. In a wood cutting machine of the character described, the combination with feed shafts for operating feed rolls for advancing the wood to a cutter, of a power shaft, a clutch keyed to said power shaft, clutches revolvably mounted on said power shaft, means to shift the power shaft relatively to the revolvably mounted clutches, a plurality of one-way reversely acting clutches on each feed shaft, means connecting each of the said revolvably mounted clutches respectively with one clutch on one feed shaft, and a rod connecting each of the other of said feed shaft clutches to the remaining clutch on the other feed shaft.

4. In a wood cutting machine of the character described, the combination with the feed shafts for operating feed rolls for advancing the wood to a cutter, of a power shaft, a clutch keyed to said power shaft, clutches revolvably mounted on said power shaft, means to shift the power shaft relatively to said revolvably clutches, a clutch case mounted on each of said feed shafts, each case being provided with an elongated arcuate slot, means connecting the feed shaft clutch cases respectively with the said revolvably clutches of the power shaft, a second clutch case on each of the said feed shafts, a rod pivotally connected to each of said second clutch cases, one end of each rod being pivotally secured to one of said second clutch cases and its other end adjustably

mounted in said arcuate slot of one of the other clutch cases on said feed shafts.

5. In a wood cutting machine of the character described, the combination with feed shafts for operating feed rolls for advancing the wood to a cutter, of a power shaft, a clutch keyed to said power shaft, clutches revolvably mounted on said power shaft, means to shift the power shaft relatively to the said revolvably clutches, a lever extending from each of said revolvably clutches, a bell crank lever secured to the upper end of each of said clutch levers, operating rods pivotally secured at one end to said bell crank levers, clutches mounted on said feed shafts and pivotally connected to the other ends of said operating rods, a second clutch secured on each feed shaft, and a bar connecting one of the first mentioned clutches of one feed shaft with one of the said second clutches on the other feed shaft.

6. In a wood cutting machine of the character described, the combination with feed shafts for operating feed rolls for advancing the wood to a cutter, of a power shaft, a clutch keyed to said power shaft, clutches revolvably mounted on said shaft, means to shift the power shaft relatively to the said revolvably clutches, a lever extending from each of said revolvably clutches, a bell crank lever secured to the upper end of each of said clutch levers, means to adjust the angularity of said bell crank lever relatively to the lever on which it is mounted, operating rods pivotally secured at one end to said bell crank levers, clutches mounted on said feed shafts and pivotally connected to the other ends of said operating rods, a second clutch secured on each feed shaft, and a bar connecting one of the first mentioned clutches of one feed shaft with one of the said second clutches on the other feed shaft.

7. In a wood cutting machine of the character described, the combination with a pair of feed shafts for operating feed rolls for advancing the wood to the cutter, of a power shaft, a pair of reversely operating one-way clutches on each feed shaft, a pair of levers loose on the power shaft, rods connecting said levers with two of the clutches on the respective feed shafts operating to turn said shafts in opposite directions, a rod connecting the other clutch on each feed shaft with the other clutch on the other feed shaft, and means for connecting either lever on the power shaft to said shaft independently of the other lever thereon.

8. In a wood cutting machine of the character described, the combination with a pair of feed shafts for operating feed rolls for advancing the wood to the cutter, of a power shaft, a pair of reversely operating one-way clutches on each feed shaft, a lever arm on the power shaft for operating one clutch of each pair, a slotted quadrant on one of the

clutches on each feed shaft, rods connecting the lever arms on the power shaft respectively with the lever arms of two of the clutches on the feed shafts, a rod connecting the lever arm of the other clutch on each feed shaft with the slotted quadrant of the other clutch on the other feed shaft, and means for connecting either lever arm on the power shaft with said shaft independently of the other lever arm on said shaft.

10 In testimony whereof I affix my signature.
JAMES E. ECKERSLEY.
